CLAIM

The ornamental design for a radio transceiver, as shown and described.

DESCRIPTION

FIG. 1 is a front, top, left perspective view of a telephone handset lifter with a lifter arm lowered showing our new design.

FIG. 2 is a front, top, left perspective view of the telephone handset lifter showing the lifter arm raised.

FIG. 3 is a top plan view of the telephone handset lifter with the lifter arm lowered.

FIG. 4 is a bottom plan view of the telephone handset lifter with the lifter arm lowered.

FIG. 5 is a front elevational view of the telephone handset lifter with the lifter arm lowered.

FIG. 6 is a rear elevational view of the telephone handset lifter with the lifter arm lowered.

FIG. 7 is a right elevational view of the telephone handset lifter with the lifter arm lowered.

FIG. 8 is a left elevational view of the telephone handset lifter with the lifter arm raised; and,

FIG. 9 is a left elevational view of the telephone handset lifter with the lifter arm lowered.

The broken lines of the Figures are for illustrative purposes only and are not a part of the claimed design.

UNITED STATES PATENT AND TRADEMARK OFFICE
CERTIFICATE OF CORRECTION

PATENT NO. : Des. 469,756 S

Page 1 of 1

APPLICATION NO. : 29/146876

DATED : February 4, 2003

INVENTOR(S) : Andrew Richardson, Soohyun Ham and Gerald Skulley

It is certified that error appears in the above-identified patent and that said Letters Patent is hereby corrected as shown below:

Title page and col. 1

The title: Radio Transceiver is incorrect. The correct title is: Telephone Handset Lifter.

Signed and Sealed this

Twenty-third Day of November, 2010

David J. Kappos
Director of the United States Patent and Trademark Office
